INVENTOR,
Otto G. H. E. Kehrkahn

UNITED STATES PATENT OFFICE.

OTTO G. H. E. KEHRHAHN, OF NEW ROCHELLE, NEW YORK.

METHOD OF PROPAGATING ELECTRIC IMPULSES IN ANTENNAE.

1,325,250.

Specification of Letters Patent. Patented Dec. 16, 1919.

Application filed October 12, 1916. Serial No. 125,231.

To all whom it may concern:

Be it known that I, OTTO G. H. E. KEHRHAHN, a citizen of the United States, residing in the city of New Rochelle, in the county of Westchester, in the State of New York, have invented certain new and useful Improvements in Methods of Propagating Electric Impulses in Antennæ, of which the following is a specification, reference being had to the accompanying drawings, forming part hereof.

The object of my invention is to generate electric impulses in antennæ for the propagation of electromagnetic waves as required in a system of wireless telegraphy and telephony. To obtain these results I employ generators in direct connection with antennæ and preferably a continuous current source of electric energy.

Referring to the accompanying drawings which form part hereof, Figure 1, is a diagram showing the instrumentalities employed in side elevation; Fig. 2, is a horizontal cross-sectional view, as indicated on line 2—2 in Fig. 1, of the same constituent parts required for carrying out my invention.

In the two diagrams, *f* represents the circular frame, *b* is the bracket attached thereto, *e* is the arcuate electrode which is concentric with the axis of frame *f*. *i* represents the material which serves to insulate electrode *e* from bracket *b*. The two ends of electrode *e* are provided respectively with storage knobs *k* and *k*¹. *g* represents the gap between the two ends of electrode *e*. *a* is the antennæ in direct connection with storage knob *k*. *a*¹ represents its grounded companion area directly connected to storage knob *k*¹. *p* represents platform for driving motor *m*. *p*¹ is bearing for motor shaft *m*. *s* represents the insulating sleeve and *s*¹ is the metallic sleeve of radial arm *s*² which is provided with telescoping post *s*³ and set-screw *s*⁴. *s*⁵ represents the contact shoe at extremity of radial arm *s*². *r* is the collecting ring for taking off the current. As shown in Fig. 2 D. C. represents the source of high-potential electromotive force for electrode *e*. *W* is the feed wire and *R* is the resistance in the said wire. *B* represents the battery as an independent source of energy for driving motor *m*. *T* represents the signaling key in the motor circuit.

With further reference to the drawings, 65 it will be seen that the fixed electrode *e* derives its high-potential electromotive force from a continuous current source through feed wire *W* connected to the positive pole of dynamo D. C. The radial arm *s*² constitutes the negative electrode of the system the current being taken off through collecting ring *r* and returned to the negative pole of dynamo D. C. thereby completing the circuit. 65

It will be obvious that the size and shape of the instrumentalities employed in carrying out my invention may be modified within wide ranges and that, if thought expedient, multiples of the device may be set 70 up without in the least departing from the basic principle of this invention, all modifications and rearrangements in this connection being considered as coming within its scope. 75

In operation, contact shoe *s*⁵ under action of motor *m* is moved along the inner face of electrode *e* in that way causing a rush of current toward the storage knob at the respective terminal of the electrode; at the 80 instant the contact shoe leaves that terminal and passes across the gap on to the other end of the electrode the circuit is first broken and then made again resulting in a discharge of current directly into the antennæ and setting up powerful electric impulses therein, the frequency of these discharges of current being dependent upon the action of the motor, which, as will be noted, has its own independent source of 85 current in battery *B* with signaling key *T* in the motor circuit for transmitting signals. 90

It will be recognized that a device of the foregoing description has great advantages 95 as regards efficiency and reliability under trying conditions, it being operative not only in an inclosure but also in the open which makes it very desirable and useful in cases where wireless communications are 100 carried on in exposed places, as for instance, on board of submarine boats and on airplanes.

I claim as my invention,

The combination of a source of electric 105 energy, an interrupted electrode connected to one pole of said source and having a gap between its ends, a second movable electrode

connected to the other pole of said source and movable in contact with the first electrode and across the gap between its ends, means to move the second electrode and 5 antennæ connected respectively and directly to the ends of the first electrode.

This specification signed and witnessed this 11th day of October, A. D. 1916.

OTTO G. H. E. KEHRHAHN
Signed in the presence of—

H. FITZGIBBON,
STUART E. NASSAW.
